UNITED STATES PATENT OFFICE.

JOHN T. HOUCHENS, OF BALTIMORE, MARYLAND, ASSIGNOR OF ONE-HALF
TO JOHN B. SISSON, OF SAME PLACE.

COUPLING FOR RAILWAY HEATING APPARATUS.

SPECIFICATION forming part of Letters Patent No. 242,201, dated May 31, 1881.

Application filed February 7, 1881. (Model.)

To all whom it may concern:

Be it known that I, JOHN T. HOUCHENS, of Baltimore city, State of Maryland, have invented certain new and useful Improvements 5 in Pipe-Couplings for Heating Apparatus for Railway-Trains; and I hereby declare the same to be fully, clearly, and exactly described as follows, reference being had to the accompanying drawings, in which—

10 Figure 1 is a plan, partly in section, of one of the pipe-elbows; Fig. 2, an elevation, partly in section, of the coupling device for connecting the pipes with the cars. Fig. 2^a is a sectional view on line *x x* of Fig. 2. Fig. 3 is a 15 side elevation of the middle joint; Fig. 4, a bottom plan of the entire system of pipes located between the platforms; Fig. 5, a bottom plan of a car, showing the direction taken by the steam-pipe; and Fig. 6 is a perspective 20 view illustrating the disposition of the parts shown in Fig. 4.

My invention has reference to devices for heating the cars of railway-trains by means of steam led from the engine through a suitable 25 system of pipes; and it has for its object to provide a strong and durable connection between the cars, adapted to admit of every possible motion of each car with reference to the next one, and of such construction that the 30 pipes will pull apart without breaking in case of the breakage of the coupler and be susceptible of ready attachment and separation when desired. My object, furthermore, is to so dispose the pipe ends with reference to the cars 35 that the connection between the cars will always present conforming parts opposite each other, no matter how the cars be turned end for end. These ends are secured by the construction and arrangement of parts shown in 40 the accompanying drawings, in which—

A is a pipe-elbow, constructed of two parts, *a a*, attached together by screws or bolts *a'*. Within each part of the elbow is a pipe, D, having a terminal flange, *d*, which rests in a 45 slot, *b*, in the swell B, as shown. The ends *b'* of the elbow are threaded, and on them are screwed nuts C, which bear upon glands E, having beveled inner edges, *e*, and compress the packing *e'* upon the pipes D. It will be 50 seen that a gas-tight joint is thus formed, while

leaving the pipes D free to turn within the elbow. The pipes D' are connected with the central coupling, M, Fig. 3, by means of a section, J, exactly similar in construction to either half of the elbow A, the terminal flange of the 55 pipe D' being secured by a slot in the swell *j*.

On the end of the part J is rigidly keyed a hand-wheel, K.

M is the middle coupling, consisting of a 60 pipe provided on its exterior with two oppositely-facing ratchets, *l l*, and a threaded section, *m'*, and a plain tubular portion, *m*, extending beyond each ratchet. Between the latter is a hand-wheel, L'.

Pawls *k*, pivoted upon the parts J, are normally thrust, by means of springs *n'*, into engagement with the ratchets, but may be held in a retracted position by means of catches *n*, which engage the outer ends of the pawls when the same are depressed.

Within the parts J are seats provided with washers or gaskets, against which the ends *m* of the part M abut when the threaded parts *m'* are screwed into the ends of the parts J. By these means the pipes J are held securely 75 together, but admit of ready separation, it being only necessary to depress one of the pawls out of engagement with the ratchet and turn the wheel L' to unscrew its threaded end from the pipe J, carrying the disengaged pawl. The 80 other pipe, J, which remains attached to the coupling M, simply turns on its pipe D', pending the unscrewing of the other end of the coupling from the opposite pipe.

The terminal pipes of the system shown in 85 Fig. 4 end in square or polygonal tubes, as shown in Fig. 2, which enter similarly-formed tubes F, that are rigidly secured to the ends of the heating-pipes. The tubes F carry in bearings on their upper sides ratchet-wheels 90 H, mounted on shafts H'. To the shafts H' are secured arms *g*, that connect with horizontal arms G, which, in turn, are pivoted to levers F', mounted in bearings *f*. The lower ends, *f'*, of the levers pass through slots in the tubes F 95 and engage with recesses I in the pipes D''. Between the ends of the latter and seats *i* in the pipe F are washers or gaskets *i*. On turning the ratchet-wheel in the direction indicated by the arrows the lever F' draws the pipe D'' 100

into the pipe F and jams its end tightly against the gasket i, making a gas-tight joint. A pawl, h, secures the ratchet-wheel H.

In Fig. 4 is shown in bottom plan the whole system of pipes between the cars. The pipe F extends from the platform and receives the pipe D'', which is bent horizontally at right angles at 1, and enters the horizontal member of one of the elbows, A. This is bent at right angles at 2, in a plane at right angles to that of the bend at 1. The pipe D of the elbow A enters a second elbow, A', bent at 3 at right angles in the same plane as the bend immediately preceding it. The pipe D of the elbow A' is rigidly screwed into a common elbow, L, curved at right angles in a horizontal plane at 4, and having a pipe, D', on the opposite side, which enters the pipe J.

The coupling M connects the system just described with an exactly similar system, bent at right angles at 5, 6, 7, and 8, and connected at its end with a pipe, F, on the next car.

It will be evident that the system of pipes is so jointed as to play freely with every possible motion of one car with reference to the next. If the cars separate or come closer together, the horizontal pipes D and D'' turn in their inclosing casings. Should one car move laterally or tilt with reference to the next, the pipes D' turn, and finally the pipes between the points 2 and 3, 6 and 7 afford the requisite play in turning a curve. In order to prevent breakage of the pipes should the cars separate, it is only necessary to provide for the release 35 of the pawls h. This may be done in many ways, such as by an arm, h', secured to the horizontal pipe between 1 and 2, which arm strikes the pawl when the pipe is caused to rotate as the cars separate, or by a light chain 40 or cord connecting the pawls with the opposite platform.

Now, it is evident that a practical device for the purpose of coupling the steam-pipes of the cars of a railway-train must be so arranged 45 that the coupling can be conveniently effected however the cars be brought together. This I attain by having the ends o' of the steam-pipe o on opposite sides of the center line of the car O, as shown in Fig. 5. It will be evident that 50 no matter how the cars be turned, the ends o'

will come opposite the termini of the system shown in Fig. 4.

With the internal arrangement of heating-pipes under the car-seats my invention has nothing to do, it relating alone to the couplings between the platforms. It may be remarked, however, that the device is equally applicable to use as coupling for air or steam or vacuum brakes, avoiding as it does the objections which lie to the use of the ordinary rubber hose.

What I claim is—

1. In a pipe-coupling, an elbow longitudinally divided and provided with slots b, in combination with pipes having terminal flanges d, glands E, and nuts C, as set forth. 65

2. In combination with the elbow A, made in two parts, a a, bolted together, and having the slots b, the flanged pipe D, nut C, gland E, having beveled edge e, and packing e', as set forth. 70

3. In combination with the pipes J, having threaded ends and pawls k, the coupling M, having double ratchet l l, and threaded portions m', as set forth.

4. In combination with the pipes J, having 75 swiveling pipes D', hand-wheels K, and ratchets l, and pawls k, the coupling M, having wheel L', as set forth.

5. In combination with the pipes J and D', the ratchets l, and pawls k, springs n', catches 80 n, and coupling M, as set forth.

6. In combination with the coupling M, having wheel L', ratchets l, threaded portions m', and tubular portions m, the pipes J, having pawls k and pipes D', as described. 85

7. In combination with the pipes F, having levers F', the tubes D'', having shoulders I, and the ratchets and pawls, as set forth.

8. In combination with the pipe F, polygonal in cross-section, and having seat i' and gasket 90 i, the pipe D'', conforming to the cross-section of the pipe F, and mechanism for compressing its end against the gasket, as set forth.

9. In combination with the square pipes F D'', the lever F', ratchet and pawls H h, and 95 gasket i, as described.

JOHN T. HOUCHENS.
